UNITED STATES PATENT OFFICE.

ALBERT F. FIFIELD, OF NEWARK, NEW JERSEY, ASSIGNOR TO THE SINGER MANUFACTURING COMPANY, A CORPORATION OF NEW JERSEY.

SEWING MACHINE.

Application filed May 1, 1919. Serial No. 294,034.

To all whom it may concern:

Be it known that I, ALBERT F. FIFIELD, a citizen of the United States, residing at Newark, in the county of Essex and State of New Jersey, have invented certain new and useful Improvements in Sewing Machines, of which the following is a specification, reference being had therein to the accompanying drawings.

10 This invention relates to an improvement in machines for sewing on buttons, but it is equally well adapted for barring, tacking and similar operations.

Machines of this type have previously 15 been operated at the relatively low speed of 1,000 or 1,200 stitches per minute.

Various difficulties have also been encountered in cutting the threads at the close of a stitching operation, and previous cutters 20 have been more or less unsatisfactory and complicated. When the last needle-loop is detained for cutting at the close of the operation, it is desirable that the work limb or limb of the loop leading to the last stitch 25 be cut and that the cut be made as close to the work as possible, as a neat finish is thereby imparted to the work, thread waste is obviated, and the limb of the loop leading to the needle is left long enough to be 30 readily gripped and held during the start of the next stitching operation. In prior machines, however, the needle-loop is in such a position that when the last one is held for cutting, its limb leading to the 35 needle is adjacent the bobbin-thread, and the limb leading to the work, which it is desired to cut, is relatively remote from the bobbin-thread. Hence it has been necessary to either provide additional devices for 40 properly deflecting or positioning the work limb of the needle-loop that it may be cut by the same severing means as used for the bobbin-thread, as shown for example in patent to Mills, No. 1,016,226, January 30, 45 1912, or else the needle and bobbin-threads are cut by different severing means, as shown in patent to Thomson, No. 702,832, June 17, 1902. In the latter event, in some cases independently operated cutters are 50 used, in others two independent cutters operating in unison, and in still others a single device having separate cutting edges for the threads is used. All of these expedients are objectionable as adding to the complication and for other reasons,

Among the objects of the present invention are to provide a machine of the type stated capable of operating at high speed, and to provide a thread-cutter therefor of the greatest simplicity and efficiency while 60 at the same time having all the features above enumerated as desirable. Other objects are to provide an improved automatic brake for the stop-motion which will lessen the shock of stopping at the high speed employed and quickly reduce the speed so that the thread-cutter mechanism, which is actuated by the stop-motion, will not act upon the thread with too great abruptness, to provide means for regulating the action of 65 the brake to suit different speeds, and to provide a combined manual and automatic tension release for the needle-thread.

In the accompanying drawings, Fig. 1 is a front side view of a machine embodying my invention. Fig. 2 is a rear side view of the same. Fig. 3 is an end view from the right in Fig. 1. Fig. 4 is an end view from the left in Fig. 1, but with the face-plate removed. Fig. 5 is a bottom plan 75 view. Fig. 6 is a detail horizontal section above the work-plate at the right-hand end of Fig. 1. Fig. 7 is a bottom plan view of the throat-plate detached, showing the cutter mechanism. Fig. 8 is a section on the line 80 8-8, of Fig. 7, showing diagrammatically the positions of the needle and bobbin-threads at the instant the cutter acts. Fig. 9 is a perspective of the movable cutter-blade. Fig. 10 is a perspective of the ledger-blade. Fig. 11 is a detail of the tension release mechanism. Figs. 6 to 11 are on an enlarged scale. Fig. 12 is a diagrammatic view illustrating the relative positions of 90 the two limbs of a needle-loop before the loop has been cast around the bobbin-thread, and Fig. 13 diagrammatically represents the relative positions of the two limbs after the loop has been cast around the bobbin-thread. 95

Referring to the drawings, the numeral 1 designates the base or work-plate of the machine from which rises the standard 2 carrying the overhanging arm 3 and head 4. A main-shaft 5 is mounted within the arm 3 and at its rear outer end carries a loose pulley 6 and a fast pulley 7. At its other end (Fig. 4) the shaft has a crank 8 with crank-pin 9 on which is pivoted a take-up 10, and a link 11 pivoted to the frame at 12 is pivotally connected to the take-up at 12'. 110

This take-up construction is similar to that shown in patent to Diehl, No. 462,398, of November 3, 1891. A link 13 is pivotally mounted at one end on an offset extension 14 of the crank-pin 9 and at its other end is pivotally secured to a collar 15 on the needle-bar 16, which latter carries at its lower end a needle 17. Within the standard 2 the shaft 5 has a bevel gear connection with a vertical shaft 18, and the latter in turn has a bevel gear connection with the rotary loop-taker shaft 19. The shaft 19 carries at its other end the loop-taker in the form of a rotary hook 20 with bobbin 21 (Figs. 4 and 5). In the present instance the gearing is such that the loop-taker makes two revolutions to each needle reciprocation. The hook is of well known form and operates in the ordinary manner to give a half twist to the needle-loop as it is cast around the bobbin-thread. The main-shaft 5 also carries a worm 22 meshing with a worm-wheel 23 on a transverse shaft 24, on which shaft is mounted a controller cam-wheel 25 (Figs. 1 and 2). A jogging work-clamp of well known form is provided, the same comprising a flat work-support 26 and a button-clamp 27. The button-clamp is supported by a pivotally mounted arched arm 28 and the latter is spring-pressed downwardly by the flat spring 29. The work-support 26 and arched arm 28 are both carried by and moved with the clamp-lever 30, and movements transversely to and longitudinally of the work-plate are transmitted to the clamp-lever by the controller cam-wheel as follows—On its outer face the cam-wheel has a cam-groove 31, and a lever 32 pivoted on the bracket 33 at 33' has a cam-follower 34 disposed in said groove. The lower end of the lever extends below the work-plate and has a ball connection with an adjustable link 35 adjustably connected with the slotted arm 36 of a pivotally mounted bell-crank-lever (Fig. 5). The other arm 37 of the bellcrank-lever is connected by a link 38 with the clamp-lever 30 and imparts movements thereto transversely of the work-plate. On the other side of the cam-wheel 25 is a cam-groove 39 (Fig. 1). A lever 40 pivoted on the bracket 33 has a cam-follower 41 at its upper end located in the groove 39. The lower end of the lever 40 is grooved to embrace the upright rod 42 carried by the clamp-lever 30. Adjustably secured to the rod 42 is a contact block 43 through which the oscillatory movements of the lower end of lever 40 are transmitted to the clamp-lever to reciprocate the latter longitudinally of the work-plate. The means above described for actuating the work-clamp are substantially those shown in patents to Sullivan, No. 777,564, of December 13, 1904 and Barron No. 1,093,241, of April 14, 1914. A stop-lever 44 is pivotally mounted in

the lug 45 on the frame for movement on an axis transverse of the work-plate, and carries a belt-shifter 46 secured near its upper end. A spring-pressed plunger 47 at the upper end of the lever is adapted when in proper position to engage a stopping cam 48 on the main-shaft 5 to stop the machine. The stop-lever also has a limited sidewise or overthrow movement after engaging the stopping cam. The stop-lever is held out of engagement with the stopping cam and in the position shown in Fig. 2 by means of a spring-pressed latch 49 which engages the rear side of the lever. At the close of a sewing operation this latch is released by a cam-lug 50 (Figs. 1 and 3) on the inner side of the controller cam-wheel 25. The stop-motion mechanism so far described is old and well known and is fully shown and described in patent to Barron, No. 1,093,241. A coil spring 51 is secured at one end to the lower end of the stop-lever 44 and at its other end to a pin 52 projecting below the base. This spring tends to move the stop-lever into stopping position. In starting, the stop-lever is moved out of alignment with the stopping cam and into engagement with the latch 49 by means of a plunger-rod 53 (Figs. 2 and 5) located below the base and adapted to contact at one end with the lower end of the stop-lever. This plunger-rod is connected at its other end to the downwardly projecting arm 54 of a bell-crank-lever pivoted to a lug on the lower side of the base. The other arm 55 of the bellcrank-lever may be connected to a treadle or other means for operating it. A coil-spring 56 surrounds the plunger-rod and is confined between a collar 57 and a bearing lug 58, which spring tends to normally hold the plunger-rod out of engagement with the stop-lever.

Owing to the high speed employed it has been found desirable to use a brake to assist the stop-motion mechanism in stopping the machine. This brake comprises a brake-shoe 59 adapted to bear against the fast pulley 7 and pivotally connected to the upper end of a brake-lever 60 pivoted on the frame at 61. A coil-spring 62 is connected at one end to the lower end of the brake-lever and at its other end to an arm 63 projecting from a short vertical shaft 64 extending through and above the base. Above the base a finger-lever 65 is connected to the shaft 64. The spring 62 tends to throw the brake into action, and by means of the finger-lever 65 and arm 63 the tension of the spring may be varied to thereby vary the action of the brake at different speeds. The brake acts only between the time the stop-lever is first tripped to shift the belt and the time the overthrow motion of the stop-lever takes place, and the following means are provided to secure the result: A small contact-lever 130

66 (Figs. 5 and 6) is pivoted at the rear of the base, one end of which lever is adapted to be actuated by the lower end of the stop-lever 44 in its sidewise overthrow movement, 5 and the opposite end of the contact-lever has a pivotal connection with a sliding bar 67 having a cam-lug 68 engaging a cam-lug 69 on the lower portion of the brake-lever. The bar 67 also has a latching projection 70 10 engageable by one end of a latch-lever 71 pivoted at 72 and pressed toward the projection by a coil-spring 73. The other end of the latch-lever 71 has a trip 74 pivotally connected thereto and yieldingly held in a 15 position at substantially a right angle to the lever by means of a coil-spring 75. A stop (not shown) on the lower side of the latch lever 71 prevents the coil-spring 75 from pulling the trip 74 too far over.

20 The thread-cutting mechanism comprises a downwardly extending bracket 76 (Fig. 7) secured to the lower side of the throat-plate and having pivotally mounted thereon a supporting arm 77 for the thread-cutter. A 25 needle-loop detaining and bobbin-thread pull-off blade 78 is secured to the arm 77 by a screw 79, which screw also secures in place a flat bobbin-thread nipper-blade 80 pressing against the part 78. Also secured 30 to the arm 77 is a barbed plate 80' which acts to nip the needle-thread at the beginning of a sewing operation in a well known manner. The detainer has an upwardly extending projection 81 forming a thread-cutting blade 82 35 with an inclined beveled cutting edge 82 (Fig. 9). This cutting edge coacts with beveled edge 83 on a ledger-blade 84 carried by a plate 85 secured to the throat-plate by a screw. Adjustment of the ledger-blade is 40 provided for by slightly elongating the screw-hole in plate 85 as shown at 86 in Fig. 8. A spring-plate 87 is frictionally engaged by the point of the needle-loop detainer after passing the needle-hole 88 in the throat-plate in order to prevent the detained needle-loop from slipping off. The throat-plate is provided with a recess 89 into which the 45 movable and ledger cutting blades project (Figs. 7 and 8). A lever 90 pivoted to the base at 91 is connected by a curved link 92 to the arm 77 (Fig. 5). At an intermediate point the lever 90 is connected by a link 93 to a lug 94 projecting from a long slide-bar 95 extending to the rear of the machine. 50 At its rear end the bar 95 carries a block 96 having a notch 97 entered by the reduced lower end of a lever 98 pivotally mounted at 99 on a bracket 100 secured to the frame (Figs. 2, 3 and 5). The upper end of lever 60 98 carries a cam-follower movable in a cam-groove 101 in the controller cam-wheel 25. The block 96 also carries a roller-stud 102 engaged by the forked arm 103 of a bell-crank-lever fulcrumed at 104, the other arm 65 105 of the lever carrying a plunger-pin 106 at its end, which pin is pressed outwardly by a spring 107. The pin 106 is adapted to enter a recess 108 in the lower part of the stop-lever 44 just before the overthrow movement of the latter takes place. The 70 above described means for actuating the slide-bar 95 and bellcrank-lever 103, 105, from the stop-lever and controller cam-wheel are substantially those shown in patent to Barron No. 1,093,241, above mentioned.

75 A presser-bar 109 is mounted in the machine head and is spring-pressed downwardly by a spring 110. A bracket 111 secured to the presser-bar has an extension 112 with an opening 113 at its upper end into which projects the reduced end of a presser-lifting lever 114 pivoted to the overhanging arm at 115. The lower end of the presser-bar has a bracket 116 secured thereto to which bracket extends beneath an angled arm 27' projecting above the button-clamp, whereby the clamp may be lifted by the presser-bar. A rearwardly projecting arm 117 is secured to the presser-bar by a split 80 collar 118 (Figs. 4 and 11), the rear end of the arm having an inclined cam surface 117' engaging a cam surface 119 on the edge of one arm of a U-shaped lever 120 pivoted in the head at 121. The other arm of the lever 90 is secured to the tension release pin of the tension 122, as shown in Fig. 4. Two angularly disposed arms 123 and 124, respectively, are secured to the free end of the presser-lifting lever 114. The arm 123 has an eye 125 95 in its free end, whereby treadle operated or other releasing means may be connected to manually lift the button-clamp and release the needle-thread tension. The arm 124 extends downwardly adjacent the periphery 100 of the controller cam-wheel and has a projection 124' at its end adapted to engage one of a pair of cam projections 126 on the periphery of wheel 25, which projections 126 are of sufficient height to cause the release 105 of the thread-tension when the arm 124 engages them.

110 The periphery of the controller cam-wheel 25 has recesses 127 formed therein (in the present case two) which recesses are out of alignment with the projections 126. An angle lever pivoted on the overhanging arm at 128 has a contact member 129 on one arm 130 adapted to engage the periphery of the controller cam-wheel in the path of the recesses 127, and a spring 131 urges said arm against the periphery of the cam-wheel. The other arm 132 of the angle-lever has 115 connected thereto a rod 133 extending forwardly into the head and having an arm 134 extending therefrom in the head. The arm 134 presses against the rear end of the lever 135 pivoted to the needle-bar at 136, the lower end of the lever being in contact with a spring needle-thread clamp 137 secured to 120 125 130

the needle-bar, which clamp tends to open when not restrained by the lever 135.

In operation the stop-lever 44 is shifted by the treadle connection of bellcrank-lever 5 arm 55, which throws the belt to the fast pulley 7, moves out the lower end of the stop-lever and allows the trip 74 to slip behind it, and allows the latch 49 to engage lever 44. The brake is in inoperative position and its operating parts are disposed as shown in Fig. 6, that is, the slide-bar 67 is latched in its extreme right hand position, its cam-lug 68 has moved out the cam-lug 69 on the brake-lever 60 against the action of the spring 62, thereby freeing the brake, and the trip 74 is in position to communicate the initial stopping movement of the stop-lever 44 to the latch-lever 71 and free the latter from the projection 70 on the slide-bar 67. As the machine starts the contact member 129 has just entered a depression or recess 127 on the controller cam-wheel, thereby allowing the thread-clamp 137 to nip the thread as the needle goes down on its first reciprocation. The tension is open, due to the projection 124' on arm 124 being on a projection 126 on the controller cam-wheel. The bobbin-thread is held nipped by the nipper 80, and the cam-follower on lever 98 is about to move off the raised portion 141 of the cam-wheel 25. The needle rises and the hook pulls the loose thread end below the throat-plate. As the follower on lever 98 passes from the portion 141 to the dwell 139 the cutting mechanism is moved partially back and the barbed blade 80' pulls the needle-thread end to one side and nips it close to the end against the throat-plate. The projection 124' also rides off the projection 126 on the cam-wheel, allowing the tension to close, and the contact piece 129 rides out of recess 127 on the cam-wheel, allowing the thread-clamp 137 to open. The stitching then proceeds in the manner usual with machines of this type. As the needle rises from its fourth reciprocation, however, the cam-follower on lever 98 leaves dwell 139 and passes into dwell 101, thereby completely withdrawing the cutter mechanism and releasing the needle-thread end when the barb 80' passes over recess 140 in the throat-plate, as at this time the needle-thread is sufficiently sewed in to hold.

At the finish of a sewing operation, the needle makes several stitches in the same hole to act as tying stitches. As the needle goes down on its last reciprocation the cam projection 50 engages the latch 49 and releases the stop-lever 44, which latter is at once acted upon by its spring and shifts the belt to the loose pulley and throws the plunger 47 into the path of the stopping cam 48. The lower end of the stop-lever, pressing on the trip 74, releases the latch 71.

The brake-lever spring 62 immediately

throws the brake into action and as the lower end of the brake-lever moves inwardly the cam-lug 69 acts upon the cam-lug 68, forcing the slide-bar 67 to the left and the lever 66 to the right and in contact with the stop-lever. The main-shaft continues to turn, due to its momentum, the needle rises, and as its loop is cast off and drawn up by the take-up the thread-cutter advances and the loop-detainer 78 pulls off the bobbin-thread and enters the loop. In Fig. 12 the relative positions of the work limb *a* and needle limb *b* of the needle-loop before the loop is cast around the bobbin-thread are diagrammatically shown, while Fig. 13 shows the manner in which the rotary hook has caused the positions of the limbs to be reversed, whereby the work limb *a* is so disposed as to be cut by the blade formerly used to cut the bobbin-thread only. The advance of the thread-cutter is caused by the passing of the follower on lever 98 up the incline to the projection 141 of the cam-wheel, which moves the slide-bar 95 connected to the cutter mechanism. The bellcrank-lever 103, 105, 90 being also connected to the slide-bar 95, is likewise moved, and its plunger-pin 106 springs into the recess 108 of the stop-lever 44 as it comes into alignment therewith. As the take-up rises to tighten the loop on the 95 detainer, the projection 124' rides up on the projection 126 of the cam-wheel, thereby releasing the tension as the take-up reaches top position. The contact piece 129 also enters recess 127 on the periphery of the 100 cam-wheel, causing the thread-clamp 137 to close, and finally the plunger 47 on the stop-lever 44 comes into engagement with a projection (not shown) on the stopping cam 48, causing a sidewise or overthrow movement 105 of the stop-lever. This overthrow movement is transmitted by the bellcrank-lever 103, 105, and slide-bar 95 to the thread-cutter to give it its final thread-cutting movement. As the follower of lever 98 is opposite the enlarged recess 138 of the cam-wheel at this time the lever 98 is free to move with the slide-bar as the cutting action takes place. As before stated, the means by which the overthrow movement is imparted is substantially that shown in patent to Barron No. 1,093,241 and forms no part of my invention. By reference to Fig. 8 it will be seen that the rotary hook has given the needle-loop a half twist, thereby disposing the 120 work-limb *a* of the needle-loop above the detainer 78 and in juxtaposition to the bobbin-thread *c*, and as the cutting edge 82 of the movable blade 81 meets the cutting edge 83 of the ledger-blade 84 the threads are simultaneously severed. The threads are cut very close to the work, less than one-quarter of an inch in actual practice, the needle-limb *b* of the loop and the bobbin-thread *c* are both left of sufficient length to readily 130

form the first stitch of the next operation, and the bobbin-thread is nipped by the spring-nipper 80. As the overthrow movement takes place the lower end of the stop-lever 5 also actuates the lever 66, which latter moves the slide-bar 67 to the right, and the cam-lug 68 on said bar acts on the cam-lug 69 to force the lower end of the brake-lever 60 outwardly and release the brake. At the 10 same time the latching projection 70 on the bar 67 comes into position to be engaged by the latch-lever 71 and the spring 73 urges the latch into engagement with the projection. As the stop-lever 44 has moved to the 15 left in its overthrow movement the trip 74 can move outwardly along the right side of lever 44 as the right-hand end of latch-lever 71 swings outwardly. As the stop-lever 44 swings back from its overthrow movement 20 it moves trip 74 slightly to the right against the tension of spring 75, and when the stop-lever is reset at the beginning of the next sewing operation its lower end moves outwardly, allowing spring 75 to pull trip 74 25 in rear of the lever again, as shown in Fig. 6.

It will be seen from the above disclosure that applicant has provided a simple and efficient thread-cutting mechanism which with a single cutter cuts both threads simultaneously and close to the work, and which requires no special deflecting or positioning means for the needle-thread loop to enable the desired limb thereof to be cut. The automatic tension release provides for the release of the needle-thread at the proper time at the finish of a sewing operation and for gripping it again at the proper time in beginning a new sewing operation, while at the same time allowing the tension to be manually released whenever the button-clamp is 40 lifted. The present machine is capable of the relatively high speed of 1800 stitches per minute, and by use of applicant's improved brake the machine is stopped without 45 undue wear and tear on the stop-motion mechanism.

Having thus set forth the nature of the invention, what I claim herein is—

1. In a sewing machine, in combination, 50 stitch-forming mechanism including a reciprocating needle, a bobbin, a loop-taker operating to give the needle-loop a half twist in casting it about the bobbin and juxtapose the bobbin-thread and the work-limb of the needle-loop, an automatic stop mechanism, and means connected to said stop mechanism for severing the juxtaposed threads.

2. In a sewing machine, in combination, 60 stitch-forming mechanism including a reciprocating needle, a bobbin, a loop-taker operating to give the needle-loop a half twist in casting it about the bobbin and juxtapose the bobbin-thread and the work-limb of the needle-loop, a take-up, an automatic stop mechanism, means for detaining the last nee-

dle-loop acted upon by the take-up, and means for severing the juxtaposed threads.

3. In a sewing machine, the combination with a reciprocating needle, a bobbin, and a loop-taker operating in a plane parallel to 70 the needle to give the needle-loop a half twist in casting it about the bobbin, and juxtapose the bobbin-thread and the work-limb of the needle-loop, of a needle-loop detaining implement, and means on said implement for severing the juxtaposed threads. 75

4. In a sewing machine, the combination with stitch-forming mechanism including a needle, a bobbin, and a loop-taker operating to give the needle-loop a half twist and juxtapose the work-limb of the needle-loop and the bobbin-thread, of a loop-detaining implement movable into the needle-loop and having a cutting edge for severing the juxtaposed threads close to the work, thereby 80 leaving the supply limb of the needle-thread long enough to start the next sewing operation.

5. In a sewing machine, the combination with stitch-forming mechanism including a 90 needle, a bobbin, and a loop-taker operating to give the needle-loop a half twist and juxtapose the work-limb of the needle-loop and the bobbin-thread, of a loop-detaining implement movable into the 95 needle-loop and having a bobbin-thread pull-off portion and a cutting edge spaced from the pull-off portion for severing the juxtaposed thread lengths close to the work thereby leaving the supply limb of the needle-thread long enough to start the next sewing 100 operation.

6. In a sewing machine, the combination with stitch-forming mechanism including a 105 needle, a bobbin, and a loop-taker operating to give the needle-loop a half twist and juxtapose the work-limb of the needle-loop and the bobbin-thread, of a thread-cutter including a blade having a point adapted to enter the last needle-loop and a pull-off edge leading from said point and adapted to engage the juxtaposed thread lengths, said blade also having a cutting edge spaced from 110 said pull-off edge, for severing the juxtaposed thread lengths close to the work. 115

7. In a sewing machine, the combination with stitch-forming mechanism including a reciprocating needle operating to throw out a loop, a bobbin, and a circularly moving loop-taker operating to pass by one side of 120 the needle in a plane substantially parallel to the path of the needle, seize said loop, and give it a half twist in casting it around the bobbin, of a thread-cutter disposed at the side of the needle opposite that passed by 125 the loop-taker and adapted to sever the bobbin-thread and the work-limb only of the needle-loop.

8. In a sewing machine, the combination with stitch-forming mechanism including a 130

reciprocating needle, a bobbin, and a loop-taker operating in a plane substantially parallel to the needle to give the needle-loop a half twist in casting it about the bobbin and 5 juxtapose the bobbin-thread and the work-limb of the needle-loop, of a pointed needle-loop detaining and severing blade, means for moving said blade into the last needle-loop in a direction substantially parallel to the 10 plane of action of the loop-taker, and means for severing the juxtaposed threads.

9. In a sewing machine, the combination with a throat-plate and stitch-forming mechanism including a reciprocating needle, a 15 bobbin, a loop-taker operating to give the needle-loop a half twist in casting it about the bobbin and juxtapose the bobbin-thread and the work-limb of the needle-loop, and stopping means for the stitch-forming mechanism, of a pointed blade adapted to enter and detain the last needle-loop and to pull off bobbin-thread, means on said blade for severing the juxtaposed threads close to the 20 needle-hole in the throat-plate, and means connected to said stopping means for operating said blade automatically as the machine 25 is brought to rest.

10. In a sewing machine, the combination with stitch-forming mechanism including a reciprocating needle, a bobbin, and a loop-taker operating to give the needle-loop a half 30 twist in casting it about the bobbin, of a blade having a pointed extremity for entering and detaining the last needle-loop and 35 positioning the work-limb of the needle-loop in juxtaposition to the bobbin-thread, means on said blade for severing the juxtaposed threads, and automatic means for operating said blade as the machine is brought to rest.

40 11. In a sewing machine, the combination with stitch-forming mechanism including a reciprocating needle, a bobbin, and a loop-taker operating to give the needle-loop a half twist and juxtapose the bobbin-thread 45 and the work-limb of the needle-loop, of a thread-cutter comprising a single pointed blade adapted to enter and detain the last needle-loop, means on said blade for severing the bobbin-thread and work-limb of the 50

needle-loop close to the work, and means on said blade spaced from the severing means for pulling off bobbin-thread and holding the needle-loop spread sufficiently to afford a needle-thread end long enough to begin a new sewing operation. 55

12. In a sewing machine, the combination with stitch-forming mechanism including a reciprocating needle, a take-up, a bobbin, and a loop-taker operating to give the needle-loop a half twist in casting it about the bobbin and juxtapose the bobbin-thread and the work-limb of the needle-loop, of a thread-cutter comprising a loop-detaining blade, means timed to move said blade into the needle-loop prior to the completion of the final 60 take-up action, and means on said blade for severing the juxtaposed threads. 65

13. In a sewing machine, the combination with a throat-plate having a needle-hole and stitch-forming mechanism including a reciprocating needle, a bobbin, and a loop-taker operating to give the needle-loop a half twist in casting it about the bobbin and juxtapose the bobbin-thread and the work-limb of the needle-loop, of a needle-loop detaining 70 blade having a cutting edge the path of movement of which passes the needle-hole, and means for causing said blade to sever the juxtaposed threads substantially at the point of closest approach of said cutting 75 edge to the needle-hole. 80

14. In a sewing machine, upper and lower stitch-forming mechanism including a needle, a bobbin, and a revolving hook whereby the needle-loop is given a half twist, a combined bobbin-thread pull-off and needle-loop detainer having a single cutting edge on its upper side, a coacting ledger cutting edge, and means for actuating said pull-off in two 85 stages at the close of a stitching operation 90 whereby the bobbin-thread is first pulled off and the last needle-loop detained and then the bobbin-thread and work-limb of the needle-loop are simultaneously severed by the cutting edges. 95

In testimony whereof, I have signed my name to this specification.

ALBERT F. FIFIELD.
